(73) Assignee: **Marquis Corp.**, Independence, OR (US)

(57) **CLAIM**

(**) Term: **14 Years**

The ornamental design for a four seat spa alcove system with spa alcove, as shown and described.

(21) Appl. No.: **29/151,210**

DESCRIPTION

(22) Filed: **Oct. 31, 2001**

FIG. 1 is a top plan view of a four seat spa alcove system with spa alcove showing the new design.

(51) LOC (7) Cl. **24-04**

FIG. 2 is a cross-sectional view of the four seat spa alcove system with spa alcove taken along lines 2—2 of FIG. 1.

(52) U.S. Cl. **D24/204**

FIG. 3 is a cross-sectional view of the four seat spa alcove system with spa alcove taken along lines 3—3 of FIG. 1.

(58) Field of Search D24/204, 205; 4/541.1, 541.2, 541.3, 541.4, 541.5, 541.6; D23/277, 280.1

FIG. 4 is a cross-sectional view of the four seat spa alcove system with spa alcove taken along lines 4—4 of FIG. 1; and,

(56) **References Cited**

FIG. 5 is a cross-sectional view of the four seat spa alcove system with spa alcove taken along lines 5—5 of FIG. 1.

U.S. PATENT DOCUMENTS

The exterior surfaces (not shown) of the spa alcove form no part of the claimed design.
